H. NORDMARK,

TOY,

APPLICATION FILED APR. 20, 1920. RENEWED OCT. 24, 1921.

1,415,682.

Patented May 9, 1922.

UNITED STATES PATENT OFFICE.

HERMAN NORDMARK, OF CHICAGO, ILLINOIS, ASSIGNOR OF ONE-HALF TO THOMAS J. JOHNSON, OF CHICAGO, ILLINOIS.

TOY.

1,415,682.

Specification of Letters Patent. Patented May 9, 1922.

Application filed April 20, 1920, Serial No. 375,351. Renewed October 24, 1921. Serial No. 510,101.

To all whom it may concern:

Be it known that I, HERMAN NORDMARK, a citizen of the United States, residing at Chicago, in the county of Cook and State of Illinois, have invented new and useful Improvements in Toys, of which the following is a specification.

This invention is a toy comprising a movable member which, in the present instance, 10 is a model of an aeroplane and which is arranged to be suspended from an elevated track and moved along the same.

The invention will be readily understood from the following description of the accompanying drawings in which;

Figure 1 is a top plan view of the invention partly broken away.

Fig. 2 is a side elevation of the same.

Fig. 3 is an end elevation thereof. 20 Fig. 4 is an enlarged fragmentary end elevation of the invention.

In the drawings an elevated track is shown comprising a vertically disposed annular rim 1 arranged to have flanged wheels 25 of a movable carriage positioned over the upper and lower edges of the rim. This annular rim is supported by cross arms 2 and 3, preferably, arranged adjacent the respective ends of an elongated annulus 30 formed by the track.

The inner adjacent ends of arms 2 and 3 are connected to an end support shown as formed of a strip bent midway of the length thereof to form the supporting rods 4 and 35 5 to which the respective arms 2 and 3 are connected. The lower ends of the supporting rods of the respective end standards are mounted upon a suitable base 6, extending beneath the entire toy. Bracing rods 7 and 40 8, preferably, extend from the outer ends of the arms 2 and 3 to the top of the supporting standard which, preferably, extends above the plane of the supporting arms 2 and 3, as shown at 9. The inner ends of the 45 brace arms 7 and 8 are, preferably, spaced apart and terminate in upwardly extending parallel flanges 10 and 11 in which a contact rod 12 is adapted to be received. This contact rod extends lengthwise of the elongated annulus formed by the track of the toy from one of the supporting standards

to the other and is electrically insulated from the flanges 10 and 11 by suitable insulating blocks 13 and 14, the contact rod being a suitable electrical conductor.

55

A contact arm carried by the movable member of the toy moving along the annular track is arranged to make sliding contact with the contact rod 12, the ends of the latter, for this purpose, preferably, extending slightly beyond the supporting arms 2 and 3 and having its ends formed as loops 15, as clearly shown in Fig. 1, in order to maintain contact between the arm of the movable carriage and the contact rod as the movable carriage moves around the curved ends of the elongated annular track.

60

The movable carriage arranged to move along the track thus formed is shown as comprising a frame having the base 16 and 70 upwardly extending side plates 17 and 18. A suspending arm 19 is shown supported from the base 16 of the carriage. This suspending arm is, preferably, arranged at one side of the longitudinal center of the movable carriage through a portion of its length in order to provide for the positioning of the wheels of the carriage in the plane of the longitudinal center of the carriage, the end of the suspending arm 16 being, preferably, 75 inwardly bent so that its supporting connection 20 with the figure toy carried thereby is approximately in the plane of the longitudinal center of the movable carriage. 80

The toy suspended from the arm 19 at 85 the connection 20 is shown, in the present instance, as a model of an aeroplane 21, it being obvious, however, that any desired toy may be thus suspended.

The wheels of the carriage are arranged 90 to respectively fit over the upper and lower edges of the rim 1 of the track and are shown at 22 and 23. These wheels are shown as each having spaced side flanges 24 fitting over the side edges of the rim 1, 95 the center portions of the rims of the wheels between the flanges resting against the edges of the rim. The wheel 22 at the upper edge of the rim 1 is shown as fast upon a shaft 25, preferably, journaled in the suspending 100 arm 19 at one side of the wheel, and in a bracket 26 at the opposite side of the wheel,

the shaft of the wheel being extended outwardly beyond the suspending arm 19 and being provided with a driving connection from the carriage of the toy.

- 5 The wheel 23 is, preferably, journaled upon a stub shaft 27 projecting from the suspending arm 19, the parts being so positioned that the wheel 23 will move along the lower edge of the rim 1. The movable carriage of the toy when mounted upon the rim of the track, as just described, is held in vertical position by the engagement of the flanges of the wheels 22 and 23 against the opposite side edges of the rim of the track, 10 15 20 25 30 35 40 45 50 55 60 65 70 75 80 85 90 95 100 105 110 115 120 125 130

The driving connection for the shaft of the wheel 22 may comprise a sprocket chain 28 moving over a sprocket wheel 29 fixed upon the shaft 25 and, preferably, arranged outside of the side plate 17 of the movable carriage. At its opposite end this sprocket chain is received over a sprocket wheel 30 fixed upon a shaft 31 extending across the movable carriage and, preferably, journaled in the side plates 17 and 18 thereof adjacent the upper end of the carriage. This shaft is, preferably, driven by a small electrical motor, the armature of which, represented at 32, is fast upon the shaft 31 and the field of which, comprising the side members 33 and 34 arranged at opposite sides of the armature 32 and the central connecting portion 35 for the side members, is, preferably, supported within the movable carriage as from a supporting bracket 36 to which the central portion 35 of the field of the motor is suitably secured.

Electrical current is supplied to the contact rod 12 and from thence is supplied to 45 the motor of the movable carriage through a contact arm 37 extending laterally from the carriage and arranged to rest upon the contact rod at its outer end in order to make electrical contact therewith. This contact 50 arm may be secured to the side plate 18 of the movable carriage as by a suitable bolt 38, electrical insulating blocks 39 being provided between this bolt and the side plate of the carriage.

55 In order to insure a good electrical contact between arm 37 and rod 12 at all times, a spring 39 is, preferably, arranged to draw the outer end of arm 37 down against the contact rod 12, the spring for this purpose 60 being shown as connected at its opposite ends to the movable carriage below the contact arm 37, as shown at 40, and to the outer end of the contact arm at its opposite end, as shown at 41.

55 An electrical connection is provided be-

tween the bolt 38 which is in electrical contact with arm 37 and the field of the motor upon the movable carriage as by a wire 42, the opposite side of the winding of the field of the motor being connected by a wire 43 to one side of the usual brushes 44 for supplying current to the armature of the motor, and the opposite terminal of said brushes being grounded upon the frame of the toy as by a wire 45.

The current supplied to the contact rod 12 may be through a wire 46 suitably electrically connected thereto, the other side of the circuit through the toy being completed by a wire 47 suitably grounded upon the frame of the toy. The circuit through the motor of the toy will thus be through the wire 46, contact rod 12, contact arm 37 and thence through wire 42, the field of the motor, wire 43, the armature of the motor, wire 45 to the frame of the toy and thence through wire 47 back to the source of electrical energy. A suitable controlling switch, not shown, may be provided in this circuit at any convenient point.

90 By the constructions set forth the movable carriage of the toy and the toy suspended therefrom are arranged to be moved around the annular track of the toy through the driving wheel 22 driven by the motor mounted upon the movable carriage as long as the controlling switch for the electrical circuit, as above described, remains closed, the starting and stopping of the toy being readily controlled by said switch.

95 Various changes may be made without departing from the spirit of the invention as claimed.

100 What is claimed is:

1. In an electric toy, an elevated track having substantially parallel elongated portions, the ends of which are connected by curved portions, a carriage movable upon said track, a toy figure suspended from said carriage, a driving motor on the carriage, an electric conductor arranged between and occupying a position substantially parallel with the parallel portions of the track and a member projecting from the carriage and adapted to contact with said conductor.

105 2. In an electric toy, the combination with a continuous track having substantially parallel portions throughout the greater portion of its length, of a carriage movable upon said track, a toy figure suspended from said carriage, a driving motor on said carriage, a single conductor positioned between and extending throughout the length of the parallel portions of the track and a member projecting from the carriage and adapted to make electrical contact with said conductor.

110 3. The combination with an elongated annular track, of an electrical contact strip extending along the longitudinal medial line of said annular track, a carriage movable

along said track, an electrical motor on said carriage for driving the same, and an electrical contact member projecting from said carriage and arranged to engage said contact strip.

4. The combination with end supporting frames, of outwardly extending arms thereon, an elevated elongated annular track supported by said arms, an electrical contact strip supported by said end frames and extending along the longitudinal medial line of said annular track, a carriage arranged to move along said track, a toy suspended from said carriage below said track, a driving 10 motor in the frame of the carriage above said track, and an electrical contact arm

projecting from said frame and arranged to engage said contact strip.

5. The combination with an elevated track having a vertical rim, of a motor supporting frame, a motor on said frame, wheels having spaced side flanges journaled on said frame and arranged to engage the upper and lower edges of said rim with said flanges at opposite sides of the rim, a driving connection between said motor and one of said wheels, and a figure toy suspended from said frame below said wheels.

In testimony whereof I have signed my name to this specification.

H. NORDMARK.
